Ringe, Boyce & Bakewell.
ATTORNEY

UNITED STATES PATENT OFFICE.

AUSTIN ROBERTS, OF PRETORIA, TRANSVAAL, SOUTH AFRICA.

TURNING SIGNAL FOR ROAD VEHICLES.

Application filed October 27, 1925, Serial No. 65,068, and in the Union of South Africa November 3, 1924.

This invention relates to turning signals for road vehicles and has particular reference to that class of signals which can be illuminated as and when desired.

5 The object of the invention is to provide a turning signal the use of which will reduce traffic accidents to a minimum by indicating the intentions of drivers to slow, stop or turn, and direction of turning. A further 10 object is to provide a signal of the kind referred to of simple construction and one which is inconspicuous when out of use and unmistakable when in use.

In accordance with my invention I provide 15 a signal composed of a plurality of arms pivotally connected together at or near their base and so arranged and combined that the arms when in operation are splayed in fan-tail formation. A further feature of my invention is the illumination of the arms from 20 a central position at or near their base thus reflecting or dispersing the light along alternate sides of the arms and so admitting a view of the signal from both back and front 25 and throwing a more or less wedge-shaped and distinctive light. A still further feature of my invention is the provision of a padded box for the reception of the arms when not in operation thus effectually preventing clatter and preserving the arms and 30 light from damage.

The arrangements above outlined adapt themselves equally well to a rising and falling action as to a horizontal action.

35 In order that my invention may be readily understood and carried into practice reference is hereby made to the accompanying sheet of illustrative drawings showing an embodiment of my invention having a rising 40 and falling action and wherein—

Fig. 1 is a side view of an example of a turning signal from the rear, with weather hood removed, the shaded portion indicating the emission of light-rays to rear,

45 Fig. 2 is a front elevation with weather hood removed,

Fig. 3 is a side elevation with weather hood from the front, the shaded portion indicating the light rays emitted to front,

50 Fig. 4 is a vertical section through the arms showing arrangement of screens in position as at Fig. 9,

Figs. 5 and 6 show respectively a plan and elevation of the means for connecting the 55 ends of the central arms,

Fig. 7 is a transverse sectional view of

upright case showing packing to deaden noise.

Figs. 8, 9 and 10 are views showing positions of signals indicating respectively stop, 60 turn and slow.

Referring to these drawings wherein like letters of reference indicate corresponding parts wherever occurring throughout all the figures, *a* designates the arms which are so constructed, arranged and combined within a box or casing *b* that when in their operative position they are splayed in fantail formation as shown.

These arms *a* the construction of which 70 is hereafter more fully described, may be composed of any suitable material such as sheet metal, aluminum or wood, are pivotally connected together at *c* and are actuated by suitable mechanism which is controlled either from the steering wheel, or the dash board or at any other point adjacent the driver. This mechanism in the example illustrated consists of a lever *d* and length 75 of Bowden wire *e*.

The box or casing *b* is closed at the sides, back and lower end and open at the front, the width of the upper arm forming the front when in its inoperative position.

The top of the box is partly closed in and 80 to assist in keeping the casing waterproof at this point a hood *f* pivoted to the top of the box at *g* is provided. This hood extends a suitable distance down the front and sides of the box when the device is out of 85 action and when in action it is lifted by the upper arm as shown in Fig. 3.

An electric bulb *h* is fitted centrally between the arms in a holder or seating on the spindle carrying the arms *a* or attached to the central arms themselves so that its movement coincides with any movement of the arms and directs its rays in the required direction. Thus when the arms are at right 90 angles to the box the light is directed on to their surfaces and when the device is in its closed position the lamp takes up its position of rest within the box or casing.

A leaf spring *j* is fitted below the bottom 95 *i* of the case *b*. Its purpose is to retain the arms (*a*) securely when they are returned by gravity to the casing *b*. A coil spring *k* is provided through which the wire *e* passes behind the packing. When tension is applied to the end of the wire *e* the spring is compressed, and exerts the force thus acquired by the leaf spring, which in turn is 100 105 110

depressed thus releasing the arms in time to respond to the pull on the wire *e*.

The upper arm is channel shaped along a portion of its length and the complete side ⁵ is returned so as to close in the end, permitting light to escape to the front only and in a more or less triangular form. The lower arm is of L-shaped formation, the angle of the upper arm taking up an opposite position to the angle of the lower arm, thus obtaining the screening effect shewn in Figs. 1 and 3 of the drawings. The two or more intermediate arms consist simply of flat strips of material the upper of such intermediate arms taking up its operative ¹⁰ position on the opposite side to the lower intermediate arm thus allowing the rays from the lamp to be projected on the inner surface of the four arms permitting a certain portion of the rays to be visible from the front and the remainder to be visible from the rear.

The degree of drop of each of the central members forming the arm is effected by the ²⁵ means illustrated in Figs. 5 and 6 from which it will be seen that the ends of each of said members are bent over at right angles and provided with a stud *l* running in slots *m*. The position of the top and bottom members ³⁰ in relation to one another is controlled either when they are tightened up on the pivot *c* or by means of slots in the sides.

The box is provided with suitable packing *n* as shewn in Fig. 7 in order to eliminate ³⁵ rattle and reduce wear and tear caused by friction to a minimum.

It may be found necessary or desirable in some instances for the two arms taking up the highest and lowest positions respectively ⁴⁰ to be of concave formation at the upper portion or edge in the one case and reversed in

the other case. This arrangement should improve reflection and the upper arm so formed will serve also as a shield covering the arms when in their closed position. ⁴⁵

The apparatus is attached to the side of the vehicle and consequently in pairs, preferably at the outer border of the windscreens so as to be within view of the driver controlling it. ⁵⁰

The improvements herein set forth are not limited to the precise construction and arrangement described for they may be embodied in various forms and modifications without departing from the spirit and scope ⁵⁵ of the invention.

What I claim is:—

1. A signal for road vehicles, comprising pivotally mounted arms angularly swingable into inclined planes different one from the other, said arms being spaced apart, and a light disposed between the arms and adapted to illuminate opposing surfaces thereof. ⁶⁰

2. A signal for road vehicles, comprising pivotally mounted arms angularly swingable into inclined planes different one from the other, means for regulating the relative angular displacement of said arms, said arms being spaced apart, and a light disposed between the arms and adapted to illuminate opposing surfaces thereof. ⁶⁵ ⁷⁰

3. A signal for road vehicles, comprising a plurality of pivotally mounted arms divided into two series, one series being spaced apart from the other, and a light disposed between said series of arms and adapted to illuminate opposing surfaces thereof. ⁷⁵

Signed at Pretoria, in the Transvaal Province of the Union of South Africa, September, 1925.

AUSTIN ROBERTS.
